TABLE CLOCK

Haruhiko Tateishi, Tokyo, Japan, assignor to Dai Nippon
Insatsu Kabushiki Kaisha, Tokyo, Japan

Filed Nov. 14, 1974, Ser. No. 523,875

Claims priority, application Japan Sept. 9, 1974

Term of patent 14 years

Int. Cl. D10—01

U.S. Cl. D10—15

FIG. 1

FIG. 2

FIG. 3

FIG. 4

FIG. 5

FIG. 5

FIG. 6

FIG. 1 is a front elevational view of a table clock showing my new design in the inactivated condition;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a left front perspective view thereof in an operative condition showing a typical time indication.

I claim:

The ornamental design for a table clock, substantially as shown.
